SMOKER'S CABINET

Fredrick H. Doerr, Lakewood, Ohio

Application October 29, 1943, Serial No. 508,219

3 Claims. (Cl. 312—71)

1

This invention relates to smokers' cabinets and has for its main object to provide a case or box having several compartments, one for holding cigarettes, another book packs of matches, and another for receiving ashes from burning cigarettes and butts of same.

Another object of the invention is to provide a smoker's cabinet of said character which is compact in arrangement, of sturdy construction, and of pleasing appearance and design for standing upon a table or desk for holding and enclosing a smoker's articles from view and provide ready and easy access thereto when desired.

Another object of the invention is to provide a smoker's cabinet of said character having a separate cover for each compartment, two of which when raised are adapted to move supporting means for cigarettes or books of matches upwardly, thereby elevating the cigarettes and matches so that same may be conveniently picked from the cabinet by the smoker, and when the covers are closed to move same downwardly within the cabinet.

Another object of the invention is to provide a support or holder in the ash compartment, which is adapted to be moved by the raising of the cover into an outer position for receiving a burning cigarette and returned within the compartment upon closing the cover and at the same time dropping the cigarette therein.

With the above and other objects in view, the invention will be described with reference to the accompanying drawings and the novel features thereof will be particularly pointed out in the appended claims.

In the drawings,

Fig. 1 is a front view of the cabinet, Fig. 2 is an end view of same, Fig. 3 is a view looking into the case with the front side removed on line 3—3 of Fig. 4, Fig. 4 is a view looking towards the left-hand end of the case part of which end is removed on line 4—4 of Fig. 3, Fig. 5 is a similar view to Fig. 4 taken on line 5—5 of Fig. 3, Fig. 6 is a front view of the right-hand end portion of the case with the covers closed and the side partially broken away on line 3—3 of Fig. 4, Fig. 7 is a plan view of the central portion of the case with the partitions therein and the relation thereto of the lift, the shelf, and the sliding plates, and Fig. 8 is plan sectional view of a corner por-

2

tion of the case and base with upright angle bar at the corner.

Referring to the drawings, the case 1 of the cabinet is of rectangular design and consists of a base 2 of suitable plate material. Fixed to the edges of the base 2 is an upright flange 3 having its upper edges turned inwardly at 4 and the corners thereof are cut out at 5 for receiving upstanding angle bars 6. Within the flange 3 of the base 2 and resting thereon is a shell 7 constructed of sheet metal and consists of front and rear sides 8—9 and ends 10—11. The lower portions of the ends 10—11 of the shell 7 are bent inwardly to form flanges at 12—13, and screws, indicated by 14, passing therethrough and through the base 2 are fixed into bars 15 serving as feet for the cabinet and secure said shell to said base. The upper edges of the sides 8—9 and the ends 10—11 are bent outwardly at 16, then downwardly at 17 and inwardly at 18. The corners of the edges 18 are also cut out at 19, as are the corners at 5 of the edges 4 of the flange 3, for receiving the upper ends of the before mentioned corner angle bars 6.

Extending from the front to the rear sides 8 and 9, and from the base 2 to beyond the upper edge 16 of the shell 7, are partitions 20 and 21 which divide said shell into a central compartment 22 and end compartments 23 and 24.

Formed integrally with the outwardly bent or upper portion 16 of the rear side 9 and located centrally of each of the compartments 22, 23 and 24 are hinge eyes indicated by 25. Covers 26, 27 and 28 are pivotally connected to the hinge eyes 25 by means of a common rod 29 passing therethrough and through pairs of hinge eyes of said covers and indicated by 30. The partitions 20 and 21 have complementary guide grooves 31—32, which are formed at their vertical edges by bending same first at a right angle and then inwardly for a purpose hereinafter described.

The central compartment 22 is adapted to hold cigarettes or if preferred, cigarettes in their original packages, indicated by 33, the end compartment 23 to hold book packs of matches, indicated by 34, and the other end compartment 24 to hold ashes and butts of cigarettes, indicated by 35. To form a tight bottom for the ash compartment 24, the flange 13 of the end 11 of the shell 7 is extended to the partition 21. For supporting the cigarettes in an upright position or one or more packages thereof after tearing away the upper portion of the package in the central compartment 22 and permitting ready access thereto when desired is arranged a lift 36 which

Fig. 8 is plan sectional view of a corner por-

is actuated by the opening and closing of the cover 26. And in the end compartment 23 for supporting the book packs of matches is a vertically movable shelf or platform 37, which is actuated by the cover 27 in the same manner and for the same purpose as the lift 36. Movable in and out of the end compartment 24 by the movement of the cover 29 is a support or holder 38 for a burning cigarette, which support also serves as a convenient place for the scraping or knocking off ashes from a cigarette, and upon the closing of the cover 28 will toss the cigarette butt into the compartment 24.

The lift 36 for supporting the cigarettes is made of sheet metal and consists of a bottom plate 40 and upright side plates 41-42 having their vertical edges bent outwardly and inwardly as at 43 for slidably engaging the partitions 20 and 21, and also providing a space 44 between said sides and said partitions. For actuating the lift 36 up and down by the opening and closing respectively of the cover 26, a pair of lever arms 45 and 46 are pivotally connected at 47 and 48 to the outside of the side plates 41 and 42 of the lift and in the spaces 44 between same and the partitions 20 and 21, and the upper ends of said lever arms are pivoted at 49 and 50 to said cover. A spacing rod 51 extends from side to side of the lift 36 at the upper rear corners, which rod also serves to hold the upper ends of the cigarettes away from the rear side of the case.

The shelf or platform 37 for supporting the book packs of matches is also constructed of sheet metal and consists of a bottom plate 52, an upright rear end or back plate 53 and a lower upright front end 54 which is bent horizontally forward to provide a ledge 55 at a height above said bottom plate for a purpose hereinafter explained. Fixed to the rear side of the front end 54 at 56 and extending above the back plate 53 is an upright plate 57 separating the shelf 37 into a front space 58 and a larger rear space 59. The front space 58 of the shelf is adapted to hold a book of matches for use and the rear space 59 several books of matches in reserve. The top edges of the back plate 53 and the separating plate 57 are curved rearwardly as indicated at 60 and 61, and the height of the plate 57 is sufficient to accommodate a book pack of matches. The shelf 37 is fixed to a slidable plate 62 having its vertical edges bent outwardly at 63 to serve as guides in the grooves 31 and 32 of the partition 20 and at the same time provide a space 64 for a lever arm 65, which is pivotally connected at 66 to said plate and at 67 to the cover 27. The raising of the cover 27 actuates the slidable plate 62 upwardly which in turn causes the shelf 37 to move in the same direction, thereby raising said shelf and the books of matches thereon above the top of the case for ready access thereto and the book of matches in the front space 58 and on the elevated ledge 55 of the shelf 37 for convenient and easy removal, and use in the usual manner, or to replace that pack when used entirely by one from the reserve space 59. And the closing of the cover 27 causes the reverse movement of the shelf 37 and the enclosing thereof and the books of matches in the case.

The support or holder 38 for a burning cigarette consists of a trough shaped dish 68 having a downwardly turned leg 69, which is pivotally connected at 70 to the end of the compartment 24. Formed integrally with the leg 69 is a lug 71 to which is pivoted at 72 a lever arm 73, the other end of which is pivoted at 74 to a lug 75 of a slid-

able plate 76. The plate 76 is similar to the plate 62, and its outwardly turned vertical edges 77 are adapted to slide in the grooves 31 and 32 of the partition 21 and provide a space at 78 between said plate and said partition. For actuating the plate 76 vertically by the movement of the cover 28, a lever arm 79 is pivotally connected at 80 to said plate and its other end at 81 to said cover. The opening movement of the cover 28 moves the plate 76 upwardly and this in turn swings the dish 68 of the support or holder 38 up and outwardly or in the arc of a circle into a position for the placing of a burning cigarette thereon, and the closing of said cover, swings the dish downwardly and inwardly or on the reverse arc, thereby tilting said dish and causing a burning cigarette butt on the dish to fall therefrom into the compartment 24. Said closing movement of the cover 28 also causes complete enclosure of the support or holder. The ashes and butts of cigarettes may be conveniently removed from the compartment 24 of the cabinet by opening its cover 28 and holding the other covers 26 and 27 closed in the palm of the hand while lifting the cabinet and turning it upside down and gently shaking same.

From the drawings and description, it is apparent that this smokers' cabinet is suitable for standing on a desk or table, is compact and convenient in arrangement for holding and enclosing from view, the cigarettes and matches and ashes or butts of cigarettes in separate compartments but permitting ready access to either the cigarettes or matches when needed, or to the use of the ash receiving compartment, by the simple opening or closing of the compartment covers. Also a support or holder for burning cigarettes or the butts of same is operated in and out of the ash compartment of the cabinet in the same manner. And the inward movement of the support or holder will toss a cigarette butt therefrom into the ash compartment. And the ashes and cigarette butts may be conveniently and quickly shaken out of the compartment without removing the cigarettes or matches from the cabinet.

Having fully described my invention, what I claim is:

1. A smoker's cabinet comprising a case, the case having a compartment for holding articles required by a smoker, a cover for said compartment, a side of said compartment having front and rear confronting vertical guide grooves thereon, a plate slidably mounted in said grooves, a shelf for supporting matches fixed to said plate, said plate having its vertical edges bent outwardly for engaging said grooves and providing space between same and said side, and a lever arm pivotally connected to said plate and in said space and to the cover of said compartment for raising and lowering said plate and shelf by the opening and closing of said cover.

2. A smoker's cabinet comprising a case, the case having a compartment for holding articles required by a smoker, a cover hinged to said compartment, a shelf in said compartment for holding book packs of matches, means connecting said cover and shelf, said shelf being actuated vertically by the movement of said cover, said shelf consisting of a horizontal plate and an offset ledge connected thereto, said plate being a greater length than said ledge for holding a plurality of book packs of matches in reserve and said ledge of a length to hold a single book pack of matches for use, and said ledge being higher than said plate whereby the book pack of matches

70

65

75

thereon is raised higher than the packs in reserve upon the opening of said cover.

3. A smoker's cabinet comprising a case, the case having a compartment for holding articles required by a smoker, a cover hinged to said compartment, a shelf in said compartment for holding book packs of matches, means connecting said cover and shelf, said shelf being actuated vertically by the movement of said cover, said shelf consisting of a bottom plate for holding a plurality of book packs of matches in reserve, the bottom plate having an upright rear portion and an upright forward portion, said forward portion terminating in a forwardly extending ledge higher than said bottom plate for holding a single book pack of matches for use and easy removal thereof when said shelf is raised by opening said cover, and an upright partition plate fixed to said upright forward portion of the bottom plate separating the single book pack of matches for use from the book packs of matches in reserve.
